(57) **CLAIM**

The ornamental design for a seat cover with floor hammock, as shown and described.

DESCRIPTION

FIG. 1 is a front elevation view of a first embodiment of a seat cover with floor hammock in accordance with the present design;

FIG. 2 is a back elevation view of the first embodiment; FIG. 3 is left and right side elevation views of the first embodiment;

FIG. 4 is a top plan view of the first embodiment;

FIG. 5 is a bottom plan view of the first embodiment;

FIG. 6 is a front elevation view of a second embodiment of a seat cover with floor hammock in accordance with the present design;

FIG. 7 is a back elevation view of the second embodiment; FIG. 8 is left and right side elevation views of the second embodiment;

FIG. 9 is a top plan view of the second embodiment;

FIG. 10 is a bottom plan view of the second embodiment;

FIG. 11 is front and back elevation views of a third embodiment of a seat cover with floor hammock in accordance with the present design;

FIG. 12 is left and right side elevation views of the third embodiment;

FIG. 13 is a top plan view of the third embodiment;

FIG. 14 is a bottom plan view of the third embodiment;

FIG. 15 is front and back elevation views of a fourth embodiment of a seat cover with floor hammock in accordance with the present design;

FIG. 16 is left and right side elevation views of the fourth embodiment;

FIG. 17 is a top plan view of the fourth embodiment; and, FIG. 18 is a bottom plan view of the fourth embodiment. The long dash broken lines immediately adjacent the claimed areas in FIG. 15 represent the bounds of the claimed design for the fourth embodiment, while the evenly spaced short dash broken lines in FIGS. 1, 2, and 11 represent stitching and form part of the claimed design for the first and third embodiments.
